Primary Examiner—Martie Thompson**[57] CLAIM**

The ornamental design for a modular organizer assembly for a ringed binder, as shown and described.

DESCRIPTION

FIG. 1 is a front, left, top perspective view of a modular organizer assembly for a ringed binder, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.
